UNITED STATES PATENT OFFICE

135,279

DESIGN FOR A SIGN OR THE LIKE

John N. Baines, Chicago, Ill.

Application January 20, 1943, Serial No. 109,291

Term of patent 7 years

To all whom it may concern:

Be it known that I, John N. Baines, a citizen of the United States, residing at Chicago, in the county of Cook and State of Illinois, have invented a new, original, and ornamental Design for a Sign or the like, of which the following is a specification, reference being had to the accompanying drawing, forming part thereof, and in which

Fig. 1 is a face view of a sign showing my new design, and

Fig. 2, a top view thereof.

I claim:

The ornamental design for a sign or the like, as shown.

JOHN N. BAINES.
